DESIGN FOR A TEAPOT OR THE LIKE

Frederick William Stark, Meriden, Conn., assignor to International Silver Company, Meriden, Conn., a corporation of New Jersey

Application September 18, 1936, Serial No. 64,914

Term of patent 14 years

To all whom it may concern:

Be it known that I, Frederick W. Stark, a citizen of the United States, residing at Meriden, county of New Haven, State of Connecticut, have invented a new, original, and ornamental Design for a Teapot or the like, of which the following is a specification, reference being had to the accompanying drawing forming a part thereof.

Fig. 1 is a side view of a teapot showing my design;

Fig. 2 is a view at right angles to Fig. 1; and
Fig. 3 is a top plan view showing the pot without a cover.

I claim:

The ornamental design for a teapot or the like, substantially as shown.

FREDERICK WILLIAM STARK.
